PAPERWEIGHT

Richard H. Van Den Berg, Glendale, Wis., assignor to Dimensional Products, Inc., Milwaukee, Wis., a corporation of Wisconsin

Filed June 15, 1965, Ser. No. 85,755

Term of patent 14 years

(Cl. D74—12)

FIG. 1 is a perspective view of a paperweight embodying my new design;

FIG. 2 is a sectional view taken on the line 2—2 of
FIG. 1; and

FIG. 3 is a top plan view thereof.

I claim:

The ornamental design for a paperweight, as shown.
